(57) **CLAIM**

I claim the ornamental design for a truck bed divider, as shown and described.

DESCRIPTION

FIG. 1 is a front perspective view of a first embodiment of the truck bed divider in an open position;

FIG. 2 is a rear perspective view of the first embodiment of FIG. 1;

FIG. 3 is a left side elevational view of the first embodiment of FIG. 1;

FIG. 4 is a front elevational view of the first embodiment of FIG. 1;

FIG. 5 is a right side elevational view of the first embodiment of FIG. 1;

FIG. 6 is a rear elevational view of the first embodiment of FIG. 1;

FIG. 7 is a top plan view of the first embodiment of FIG. 1;
FIG. 8 is a bottom plan view of the first embodiment of FIG. 1;

FIG. 9 is a rear perspective view of the first embodiment in a closed position;

FIG. 10 is a front perspective of a second embodiment of the truck bed divider in an open position;

FIG. 11 is a rear perspective view of the second embodiment in FIG. 10;

FIG. 12 is a left side elevational view of the second embodiment in FIG. 10;

FIG. 13 is a front elevational view of the second embodiment in FIG. 10;

FIG. 14 is a right side elevational view of the second embodiment in FIG. 10;

FIG. 15 is a rear elevational view of the second embodiment in FIG. 10;

FIG. 16 is a top plan view of the second embodiment in FIG. 10;

FIG. 17 is a bottom plan view of the second embodiment in FIG. 10; and,

FIG. 18 is a rear perspective view of the second embodiment in a closed position.

The drawings show symbolic breaks in length shown as parallel lines broken by a zigzag. The appearance of any portion of the article between these break lines forms no part of the claimed design.
